UNITED STATES PATENT OFFICE

WALTER A. ABEGG, OF LOS ANGELES, CALIFORNIA, ASSIGNOR OF ONE-HALF TO B. REINHOLD, OF LOS ANGELES, CALIFORNIA

DRILLING BIT

Application filed August 26, 1929. Serial No. 388,410.

This invention has to do with a drilling bit and relates more particularly to a bit for drilling wells, or the like. It is a general object of the invention to provide an improved, effective and commercially practical bit suitable for well drilling.

It is another object of the invention to provide a practical, dependable construction for mounting cutters on a shank so that they can be varied as to position, with relation to the shank. By the present invention a single bit construction can be used to drill holes of different sizes, this being made possible by varying the cutters on the shank.

Another object of the invention is to provide a bit construction in which the cutters are mounted on the shank through carriers, the carriers being secured to the shank through a simple, inexpensive and dependable construction.

A further object of the invention is to provide a bit construction of the character mentioned in which the cutter carriers are secured to the shank by a plurality of independent means, making the construction particularly secure and dependable.

It is another object of the invention to provide a bit construction in which the wear receiving parts, that is, the cutters and their carriers, are of simple, inexpensive construction making the tool inexpensive to maintain in proper operating condition. The cutter carriers are so related to the body as to protect or shield the body against wear.

The various objects and features of my invention will be best and more fully understood from the following detailed description of a typical form and application of the invention, throughout which description reference is had to the accompanying drawings, in which:

Fig. 1 is a side elevation of a bit embodying the construction provided by this invention. Fig. 2 is a vertical detailed sectional view of the bit. Fig. 3 is a detailed transverse sectional view of the bit taken as indicated by line 3-3 on Fig. 1, and Fig. 4 is a detailed transverse sectional view of the bit taken as indicated by line 4-4 on Fig. 1.

The bit provided by this invention in-

cludes, generally, a shank 10, cutters 11, and carriers 12 for mounting the cutters on the shank. The invention may be carried out in bits having cutters of different forms or types, it being particularly applicable, however, to bits ordinarily known as "rock" bits in which the cutters are of the roller type. In the particular embodiment of the invention illustrated the cutters are conical cutters and the construction embodies two cutters arranged diametrically opposite each other at the lower end of the tool with their axes converging downwardly. This arrangement of cutters is a common and typical arrangement which will serve to facilitate an understanding of the present invention.

The shank 10 includes, generally, a body 13, an enlarged portion or head 14 at the upper end of the body 13, and a tapered pin projection 15 on the upper end of the head to facilitate connection of the tool with a string of drill pipe 16, or the like. The main or body portion 13 of the shank is flattened at opposite sides so that it has flat side faces 17. The lower end portions 18 of the faces 17 are preferably pitched or tapered inwardly, forming seats for the cutter carriers as will be hereinafter described.

The head portion of the shank is preferably substantially round in cross section. In the particular form of the invention illustrated opposite sides 19 of the head are somewhat flattened, the flattened parts 19 continuing downwardly along the body 13 making the body rectangular in cross section, as clearly shown in Fig. 3. The tapered screw-threaded projection 15 at the upper end of the shank may be of the type commonly provided on well tools for purpose of making a connection with an adjoining part. A central longitudinal circulation opening 20 extends through the shank from the upper end of the pin projection 15 to the lower end of the body 13. The opening 20 has a reduced or restricted portion 21 at the lower end of the body to operate as a nozzle for directing the fluid downwardly onto the cutters which are located below the lower end of the body 13.

Each cutter illustrated in the drawings is in the nature of a unit or assembly including a bushing 22 and a cutter proper 23 rotatably mounted on the bushing. The bushing and cutter are keyed or locked together by a retaining member 24. The bushing 22 fits an opening 25 extending into the cutter from its base end. The bushing is preferably provided with a radial flange 26 which overlaps the base of the cutter, as clearly shown in Fig. 2 of the drawings. The cutter carriers 12 operate to mount or support the cutters 11 on the shank 10. In the particular case illustrated there is one cutter on each carrier and the bit includes two cutters so therefore there are two cutter carriers 12. Each carrier 12 includes a block 28 to be arranged at one of the side faces 17 of the body 13 and a pin or stud 29 to carry the bushing 22 of a cutter assembly 11. The block 28 has a flat inner side 30 adapted to fit against the side face 17 of the body 13 and has a curved outer face 31 substantially concentric with the longitudinal axis of the tool. The block 28 is provided with a shoulder 32 at the lower end of the face 30 to oppose the seat 18 at the lower end of the body 13. In the preferred construction a washer or spacer plate 33 is arranged between the seat 18 and shoulder 32 in a manner such as is illustrated in the drawings. The block 28 projects downwardly or below the lower end of the body 13. The projecting portion of the block 28 has its under side finished to present a downwardly and outwardly extending face 34 on which the cutter 11 is adapted to be mounted. The cutter mounting pin or stud 29 projects from the face 34 and is perpendicular to the face 34. The pin 29 is screw threaded and the bushing of the cutter assembly is provided with a screw-threaded socket 35 so that the bushing 22 can be applied to the pin in the manner clearly illustrated in Fig. 2 of the drawings. In practice it is desirable to insert a washer 36 between the flange 26 of the cutter bushing and the face 34 of the carrier block 28.

The present invention provides means for mounting the cutter carriers on the body, and in the preferred form of the invention each carrier is connected to the body at two points. In the construction illustrated each carrier block has its upper end connected to the shank. The connection between the upper end of the block and the shank is a pivotal connection allowing the block to be shifted or swung with relation to the shank to vary the spacing of the cutter 11 with reference to the central axis of the tool. The connection at the lower end portion of the shank is immediately adjacent the cutter carrying portion of the shank and is in the nature of a clamp means operating to firmly and securely unite the cutter carrying block and the body 13 of the shank.

In the specific construction illustrated each cutter carrying block 28 is provided at its upper end with a tongue 40 projecting between spaced lugs 41 projecting downwardly from the head 14 of the shank and joining the faces 17 of the shank. A pivot pin 42 extends through the lugs 41 and tongue 40 pivotally connecting the cutter carrying block with the shank of the tool. In the construction illustrated the pivot pin is held in place by a set screw 44 extending into the tongue 40 from its inner side and engaging the side of the pin in the manner clearly illustrated in Fig. 2 of the drawings. By this particular locking arrangement the pivotal connection cannot work loose as the set screw 44, which holds the pin in place, cannot become displaced unless the cutter carrying block 28 is swung away from the body of the shank. It is preferred to curve the lower ends of the lugs 41 concentric with the axes of the pins 42 and to correspondingly curve the upper ends of the blocks so that up thrust, or strain, is taken between the blocks and lugs and not through the pins.

The clamping means provided for holding the lower end portion of the cutter carrying block to the body 13 of the shank may be in the form of a bolt construction. In the case illustrated two bolts 50, located at diametrically opposite sides of the central axis of the tool, extend through the two cutter carrying blocks 28 and through the lower end portion of the body 13, clamping these parts firmly together. The bolts are preferably located so that they also extend through the spacer blocks 33 and thus operate to hold the blocks in place between the body 13 and the cutter carrying blocks 28. The ends of the bolts 50 are preferably countersunk in recesses 55 provided in the outer side of the cutter carrying blocks 28, as clearly shown in Fig. 4 of the drawings.

It is preferred to provide spherically faced washers under the heads and nuts of the bolts and to fit the bolts through the blocks so that change in angle of the blocks does not put bending strains on the bolts.

Through the arrangement and construction just described each cutter carrying block 28 is held immediately adjacent the cutter supporting part by the two bolts 50, thus making the construction particularly secure and dependable. It is also to be noted that the positioning of the bolts and the general formation of parts permits of the bolts 50 being comparatively large, or heavy, thus giving the construction great strength and rigidity. It is also to be noted that the hinge construction between the upper ends of the cutter carrying blocks and shank may be sturdy and such as to effectively brace the blocks with reference to the shank.

In using the tool the parts are assembled as is shown in the drawings, the pivotal con-

nections being locked by the set screws 44 and the bolts 50 being made tight so that the cutter carriers and shank form a rigid unitary construction firmly supporting the cutters 11 in position for operation. When it is desired to repair or replace the cutters, the bolts 50 may be released and the carrier blocks 29 swung away from the body of the shank, making the cutters 11 accessible so that they can be removed from the mounting pins 29. It will be obvious that the cutters cannot become displaced or removed from the pins 29 when the carrier blocks 28 are in place against the shank, as shown in the drawings. The construction provided by the invention makes it possible to space the cutters 11 various distances from the central axis of the shank, it being obvious that this permits of the use of cutters 11 of different sizes, as cutters of larger diameter can be used when the blocks are spread further apart than when the blocks are close together, or permits the same cutters to be spaced different distances apart to drill different-sized holes. By arranging spacer blocks 33 of different thicknesses or sizes between the cutter carrying blocks 28 and the body of the shank, the cutters may be spaced in any desired manner.

Having described only a typical, preferred form of my invention, I do not wish to limit myself to the specific details set forth, but wish to reserve to myself any changes or variations that may appear to those skilled in the art or fall within the scope of the following claims:

Having described my invention, I claim:

1. In a bit of the character described, a shank, a carrier having one end pivotally attached to the shank, means intermediate the ends of the carrier holding the carrier against pivotal movement, a spacer block between the shank and carrier at a point spaced from the pivotal axis of the carrier, and a cutter on the carrier.

2. In a bit of the character described, a shank having a face, a carrier pivotally connected to the shank, a face on the carrier, a spacer block between the said faces, means for clamping the carrier toward the shank to clamp the spacer block between the faces, and a cutter on the carrier.

3. In a bit of the character described, a shank having an inclined face, spaced lugs on the shank above said face, a carrier having an inclined face opposite the face of the shank and a part extending between the lugs, a pin extending through the lugs and said part of the carrier, a spacer block, a bolt extending through the shank and carrier and clamping the spacer block between the faces, and a cutter on the carrier.

4. A bit including, a shank, a plurality of carriers pivotally connected to the shank, spacer blocks between the carriers and the shank, means spaced from the pivotal axes of

the carriers for clamping the carriers toward the shank, and cutters on the carriers.

5. A bit including, a shank, a plurality of carriers pivotally connected to the shank, spacer blocks between the carriers and the shank, means spaced from the pivotal axes of the carriers for clamping the carriers toward the shank, including a bolt extending through the shank, spacer blocks, and carriers, and cutters on the carriers.

6. A bit including, a shank having inclined faces, a plurality of carriers pivotally connected with the shank and having inclined faces opposite the inclined faces on the shank, spacer blocks between the inclined faces of the shank and carriers, means for holding the carriers against pivotal movement and for clamping the spacer blocks in position, and cutters on the carriers.

7. A bit including, a shank having faces on opposite sides, a carrier pivoted on each of the said opposite sides of the shank, cutters carried by the carriers, spacer blocks between the carriers and said faces and releasable means for holding the carriers against pivotal movement, and for clamping the spacer blocks in position.

In witness that I claim the foregoing I have hereunto subscribed my name this 24th day of July, 1929.
